WEFT LAYING NEEDLE MECHANISM FOR
AXMINSTER LOOMSHerbert A. Whitin, Worcester, Mass., assignor to
Crompton & Knowles Loom Works, Worcester,
Mass., a corporation of MassachusettsOriginal application March 26, 1946, Serial No.
657,266. Divided and this application July 9,
1947, Serial No. 759,752

6 Claims. (Cl. 139—123)

1

This is a division of my copending application Serial No. 657,266, filed March 26, 1946, now abandoned.

This invention relates to improvements in Axminster looms and it is the general object of the invention to provide a flexible weft laying needle which can be driven by a rotary actuator such as a sprocket wheel.

It is customary in Axminster looms to introduce the weft by means of an elongated needle which is guided by a needle rail extending from one side of the loom. This rail is about as long as the loom is wide and occupies an objectionably large amount of floor space. It is an important object of my present invention to provide a weft laying needle of flexible sheet metal provided with transverse ribs or the like which cooperate with a rotary actuator located at one side of the loom. The needle curves around the sprocket and then leads upwardly instead of laterally from the loom and for this reason the loom occupies considerably less floor space.

In the form of the invention shown herein-after I utilize a flat strip of metal which may be crimped or otherwise provided with transverse ribs to cooperate with a sprocket wheel having a substantially cylindrical periphery provided with notches or the like which receive the ribs.

In an Axminster loom a needle ordinarily lays a double pick which is looped by a selvage shuttle at that side of the loom opposite the needle operating mechanism. Ordinarily a short interval of time must be provided to allow the selvage shuttle to pass through the loop of weft. It is another object of my present invention to provide a rotary actuator or sprocket so made that when its direction is reversed to retract the needle from the warp shed there will be a time lag before its teeth engage the transverse ribs of the needle sufficiently long to permit the selvage shuttle to perform its weft locking operation.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a part of an Axminster loom having my invention applied thereto,

Fig. 2 is a plan view looking in the direction of arrow 2, Fig. 1 showing the needle in the shed and the selvage shuttle performing its weft locking operation,

2

Figs. 3 and 4 are enlarged vertical sections on lines 3—3 and 4—4, respectively, of Fig. 2,

Fig. 5 is an enlarged rear elevation looking in the direction of arrow 5, Fig. 2,

Fig. 6 is an enlarged view of the eye end of the needle, and

Fig. 7 is a diagrammatic view indicating the manner in which reversal of the operating sprocket provides a dwell during the time of operation of the selvage shuttle.

Referring particularly to Figs. 1 and 2 I have shown the loom frame 10 of an Axminster loom having the usual front and back tuft cutter blades 11 and 12 and also parts of the transfer mechanism which remove tube frames from the transporting chain. These latter parts include an arm 13, a tube frame 14, and a transporting chain 15 moving around a pullover shaft 16 mounted as at 17 on the loom frame. The loom lay 18 having a beat-up reed 19 is operated in the usual manner and is held in rear position during weft needle insertion and then beats forwardly or to the left as viewed in Fig. 1. The upper and lower warp sheds are indicated at W and W' and the cloth at C.

At the left side of the loom as viewed in Fig. 2 there is a stationary race 20 for a selvage shuttle 21 operated by an arm 22 at the upper end of a vertical shaft 23. The latter has a lower arm 24 secured thereto for attachment to an operating rod 25. The rod 25 is reciprocated to rock the arm 22 first backwardly and then forwardly for each pick of the loom. Shuttle 21 carries the usual package of selvage locking weft not shown and has its rearward operating motion while the weft laying needle is in the warp shed.

The parts of the loom thus far described operate in their usual manner, the transfer arm 13 preferably having a motion every third pick of the loom and the lay beating up three times for a complete tuft forming operation.

In carrying my invention into effect I provide a stationary stand 30 secured to the loom frame and supporting a casing 31 in which is rotatably mounted a horizontal shaft 32. A guide block 33 forming part of the casing 31 has a curved surface 34 concentric with the shaft 32 and has horizontal and vertical guide surfaces 35 and 36, respectively, which merge with the arcuate surface 34.

The casing has side walls 40 supporting the shaft 32 and between which is located a sprocket wheel 41 pinned to the shaft 32. A gear 42 is secured to shaft 32 and meshes with a vertical reciprocable rack rod 43 sliding in top and bot-

tom guides 44 and 45, respectively, secured to the side of the casing. The rack rod 43 is pivoted at its lower end to a connector rod 46 which is driven by a crank arm 47 on the forward end of a stub shaft 48 rotating in a fixed bearing 49. A bevel pinion 50 on the rear end of shaft 48 is in position for cooperation with groups of beveled gear teeth on a driving gear 51 secured to a loom shaft 52. Gear 51 turns continuously during loom operation and its three groups of teeth indicated at 53, 54 and 55, respectively, mesh with the bevel pinion 50 intermittently and in rotation. The segments or groups 53, 54 and 55 are sufficiently long to give a complete rotation to the bevel pinion 50 and therefore cause a complete reciprocation of the rack rod 43 for each segment and pick of the loom.

The sprocket wheel 41 has a generally cylindrical periphery 60 provided with cross grooves 61 lying between driving teeth 62. The teeth are transverse of the periphery of the sprocket 41 and are substantially straight from side to side of the sprocket.

The needle designated at N is made preferably of a strip of sheet metal 65 which is normally flat and flexible and also preferably resilient. The strip 65 is provided with cross ribs 66 struck therefrom and extending transversely thereof and spaced uniformly along the length of the needle N. These ribs 66 enter the grooves 61 and cooperate with the teeth 62 to effect movement of the needle when the sprocket 41 is turning. The left end of the needle as shown in Fig. 6 is provided with an eye element 70 having a yarn eye 71 for the weft F. The weft is derived from a stationary package not shown and leads through well-known guides to the eye 71 and thence to the selvage of the cloth C.

At the start of a pick the eye 71 will be at the right end of the loom and when the warp shed is open and the lay is temporarily at rest, in rear position the rack rod 43 will be raised by bevel gear 51 and cause clockwise rotation of sprocket 41 as viewed in Fig. 3, thereby causing the teeth 62 to engage the cross ribs 66 and move the horizontal part of the needle toward the left through the warp shed. A guide 72 supported by the stand 30 may be provided to direct the eye element 70 of the needle into the warp shed.

Rotation of sprocket 41 will continue until the needle is fully inserted into the shed as shown in Fig. 2. The selvage shuttle 21 will then start on its backward motion to pass through the loop of filling F and rack rod 43 will immediately start to turn in the opposite direction due to operation of the crank arms 47. Due, however, to the length of the slots or grooves 61 the teeth 62 will not immediately engage ribs 66 and start of retraction of the needle will be delayed during the first part of the counter-clockwise turning movement of sprocket 41 as viewed in Fig. 3. During this slight delay the selvage shuttle passes through the loop of weft after which the teeth 62 engage the cross ribs 66 and movement of the needle to the right, Fig. 2, will start. This relationship is shown in Fig. 7, in which the full lines indicate the position of the sprocket relatively to the needle at the end of the insertion stroke of the needle during which the sprocket turns in the direction of arrow a. The sprocket then turns in the reverse direction as indicated by arrow b and retraction of the needle does not start until the sprocket reaches the dotted line position. Thereafter continued left hand turning of the sprocket 41 will move the

horizontal part of the needle out of the warp shed and along surface 35 and the vertical part of the needle will extend upwardly along the vertical guide surface 36 and then along any suitable guide 13, see Figs. 1 and 3. This operation occurs three times for each complete tuft forming cycle of the loom.

From the foregoing it will be seen that I have provided a simple form of weft needle for Axminster loom made of a strip of flexible and preferably resilient metal provided with longitudinally spaced cross ribs for cooperation with a driving sprocket. It will further be seen that the distance between adjacent teeth 66 on the sprocket is appreciably greater than the width of a rib 66 measured longitudinally of the needle, and that this relationship permits a dwell in the motion of the needle when the latter is cooperating with the selvage shuttle immediately prior to retraction of the needle and during the first part of the reverse motion of the sprocket. Although I have shown the transverse ribs of the needle as struck integrally therefrom I do not wish necessarily to be limited to this specific form of rib.

The mechanism for operating the needle is not claimed herein, but is the subject matter of the parent application of which this is a division.

Having thus described my invention it will be seen that changes and modifications may be made therein by those skilled in the art without departing from the spirit and scope of the invention and I do not wish to be limited to the details herein disclosed, but what I claim is:

1. A needle for an Axminster loom having a toothed rotary actuator rotatable in opposite directions, the needle comprising an elongated strip of resilient sheet metal having side edges and being continuous and uninterrupted from edge to edge, said strip having transverse ribs by means of which the needle can be moved into and out of a warp shed and having a weft eye at one end thereof.

2. In a weft laying needle for an Axminster loom having a rotary actuator having peripherally spaced recesses, said needle comprising an elongated strip of resilient sheet metal having side edges and being continuous and uninterrupted from edge to edge, said strip having longitudinally spaced transverse ribs to enter said recesses and cooperate with the actuator for the purpose of moving the needle into and out of a warp shed, and a weft eye at one end of said strip.

3. In a needle for an Axminster loom having a rotary actuator having peripherally spaced transverse grooves, said needle comprising an elongated resilient metallic strip having side edges and being continuous and uninterrupted from edge to edge, said strip having struck therefrom and integral therewith longitudinally spaced transverse ribs for entry into said grooves, and a weft eye at one end of said strip.

4. A needle for an Axminster loom having a toothed rotary actuator rotatable in opposite directions, the needle comprising a strip of sheet resilient metal having side edges and being continuous and uninterrupted from edge to edge, said strip having struck therefrom longitudinally spaced transverse integral ribs all of which lie on one side of said needle for cooperation with the actuator.

5. In a weft laying needle for an Axminster loom having a reversible rotary actuator formed with peripherally spaced grooves of a given width

measured circumferentially of the actuator, said needle comprising an elongated strip of resilient sheet material having longitudinally spaced transverse ribs of less width measured lengthwise of the needle than said given width of said grooves, said ribs to enter said grooves and cooperate with the actuator for the purpose of moving the needle into and out of the warp shed, and produce a dwell in the motion of the needle when the actuator is reversed, and a weft eye member on one end of the needle.

6. In a weft laying needle for an Axminster loom having a reversible rotary actuator having teeth spaced apart a given distance circumferentially of the actuator, said needle comprising an elongated flexible strip formed with cross ribs spaced along the strip, the distance each cross rib extends lengthwise of said strip being less than said given distance, said ribs to cooperate with said teeth to move the needle into and out

of the warp shed and produce a dwell in the motion of the needle when the direction of turning of the actuator reverses.
